United States Patent Office

Des. 204,444

Patented Apr. 19, 1966

204,444

AIR CUSHION OR SIMILAR ARTICLE

William M. Emery, 44 Pittsford Way,
New Providence, N.J. 07974

Filed Sept. 10, 1965, Ser. No. 86,941

Term of patent 14 years

(Cl. D3—9)

FIG. 1

FIG. 2

FIG. 1 is a front elevational view of an air cushion or similar article showing my new design, the back being identical thereto; and

FIG. 2 is a side view thereof.

I claim:

The ornamental design for an air cushion or similar article, as shown and described.
